Filed Aug. 26, 1965, Ser. No. 86,725

Term of patent 14 years

(Cl. D26—5)

FIG. 1.

FIG. 2.

FIG. 3.

FIG. 4.

FIG. 5.

FIG. 1 is a top and front perspective view of a housing for electrical equipment, showing my new design;

FIG. 2 is a top plan view;

FIG. 3 is a side elevational view, the opposite side being substantially a mirror image thereof;

FIG. 4 is an end elevational view, the opposite end being substantially a mirror image thereof; and

FIG. 5 is a bottom plan view thereof.

The dominant features of my new design are shown in solid lines in the drawing. The supporting cable and clamps shown in broken lines in FIG. 1 and the clamps shown in broken lines in FIG. 2 are for illustrative purposes only.

I claim:

The ornamental design for a housing for electrical equipment, as shown and described.
